CLAIM

The ornamental design for mini storage silo, as shown and described.

DESCRIPTION

FIG. 1 is a front perspective view of our mini storage silo showing our new design;

FIG. 2 is a side elevation of the mini storage silo as viewed from the right side of the mini storage silo as shown in FIG. 1;

FIG. 3 is a side elevation of the mini storage silo as viewed from the left side of the mini storage silo as shown in FIG. 1;

FIG. 4 is a rear elevation of our mini storage silo viewed from the back side of the silo shown in FIG. 1;

FIG. 5 is a bottom elevation of the mini storage silo; FIG. 6 is a top elevation or plan view of our mini storage silo; and,

FIG. 7 is a rear elevation identical to FIG. 4 but illustrating a modified form of our mini storage silo where a doorway.

*Fig. 1**Fig. 2**Fig. 3*

*Fig. 4**Fig. 5**Fig. 6*
